G. E. MOLYNEUX.
PROCESS OF JOINING FABRIC SECTIONS.
APPLICATION FILED MAY 18, 1917.

1,384,845.

Patented July 19, 1921.

UNITED STATES PATENT OFFICE.

GEORGE E. MOLYNEUX, OF BAYONNE, NEW JERSEY, ASSIGNOR TO THE SINGER MANUFACTURING COMPANY, A CORPORATION OF NEW JERSEY.

PROCESS OF JOINING FABRIC SECTIONS.

1,384,845.

Specification of Letters Patent. Patented July 19, 1921.

Original application filed March 24, 1913, Serial No. 756,817. Divided and this application filed May 18, 1917. Serial No. 169,422.

To all whom it may concern:

Be it known that I, GEORGE E. MOLYNEUX, a citizen of the United States, residing at Bayonne, in the county of Hudson and State of New Jersey, have invented 5 certain new and useful Improvements in Processes of Joining Fabric Sections, of which the following is a specification, reference being had therein to the accompanying 10 drawings.

This invention relates to new and useful improvements in processes of joining fabric sections and more particularly to a process of forming a covering seam for previously 15 joined edges of fabric sections.

In the work of covering seams it has heretofore been the usual practice, as evidenced, for example, by the patents to Muther *et al.*, No. 583,415; Borton, No. 710,942; Perry, No. 20 776,683, to first close the seam by either a through-and-through or overlock stitch, and then to cover the opened out seam upon a plural needle machine, the gage of which is wide enough to embrace the initially formed 25 seam and cover the raw edge portions of material. When covering light and elastic goods the action of the covering stitch tends to draw or pucker the goods thereby forming a ridge on the upper side of the goods. 30 To prevent this it has been the usual practice to run the lower or seam covering thread under very loose tension. The present process has been devised for use, more particularly, for seam covering, the object being 35 to provide a process whereby the work may be spread or placed under a lateral strain before the covering stitch is applied, thereby obviating the objectionable ridge on the upper side of the work and causing the 40 finished seam to lie substantially flat.

The above and other objects will in part be obvious and will in part be hereafter more fully disclosed.

In the accompanying drawings, Figure 1 45 is a side elevation of a machine which may conveniently be used for carrying the invention into effect. Fig. 2 is a top view of the throat-plate and feed-dog of the machine. Fig. 3 is a perspective view of the feed-dog 50 and its support; Fig. 4, a perspective view of one of the movable feed-dogs; Fig. 5, a perspective view of the throat-plate; Fig. 6, a section on the line 6—6 of Fig. 2. Fig. 7 is a transverse section on the line 7—7,

Fig. 2, showing unstretched work of an exaggerated thickness before it reaches the needles. Fig. 8 is a similar view on the line 8—8, Fig. 2, showing the spread or stretched work after it has been stitched. Fig. 9 is an enlarged diagrammatic cross-sectional view showing two superposed fabric sections initially stitched by the usual through-and-through stitching. Fig. 10 is a similar view showing the fabric sections of Fig. 9 opened out flat and covered in accordance 65 with the present method. Fig. 11 is an enlarged diagrammatic cross-sectional view showing two superposed fabric sections initially stitched by the usual overlock stitching and Fig. 12 is a similar view showing 70 the fabric sections of Fig. 11 opened out flat and covered in accordance with the present method.

The invention, as described herein, in connection with a convenient machine or mechanism for carrying it into effect, will be readily understood by referring to the drawings, in which the numeral 1 designates the arm of the machine, 2 the cylinder-bed, 3 the needle-bar, 3', 3' the needles carried thereby, 4 the presser-foot bar, 4' the presser-foot lifter, and 5 the power-shaft. The needles 3', 3', are adapted to coöperate as usual with the well known covering thread-handling element or looper 3*. These parts 75 are all of well known construction. As disclosed in my Patent No. 1,356,938, dated October 26, 1920, of which this application is a division, the feed-dog of the machine may comprise a shank 6 secured to the carrier 7 by a screw passing through an elongated slot 8 in said shank to permit of proper adjustment on the carrier. The shank 6 is 90 formed with a T-head 9 having a lengthwise undercut slot 10 adapted to receive the feed-dog sections and to hold them against longitudinal movement independently of the shank. The feeding surfaces comprise the two outside or auxiliary feed-dog sections 11 and 12 each of which has an integral base 100 13, or a base made in a separate piece and secured to the feeding surface, corresponding, in section, to the undercut slot 10 and freely movable therein lengthwise of the T-head, or laterally of the center line of the cylinder. The outer sections 11 and 12 are 105 set at an angle to their bases so as to diverge outwardly in the direction of the line of

- stitching, that is, they diverge outwardly from the operator, the angle of divergence of said sections corresponding to the openings 16 and 17 in the throat-plate. The degree of divergence of the feed surfaces 11 and 12, relatively to their bases, may be greater or less than that shown in the drawings, according to the character of the work; as for example with a ribbed fabric sewed lengthwise of the rib or with the wale, it is desirable that the angle of divergence be greater than when stitching flat knitted fabrics. As seen more particularly in Fig. 2, the teeth of the sections 11 and 12 are cut at right angles to the side walls of the sections and certain of said teeth of each section are disposed in advance of the needles and are thus adapted to act upon and stretch the fabric before it reaches the needles.
- Between the end sections 11 and 12 is a main feed-dog section 14 shown as having two feeding surfaces although it may be made with a single feed surface, the teeth on said section or sections being at right angles to the base which is similar to the base 13, shown in Fig. 4. The feeding surfaces of the main feed-dog section 14 are disposed in rear of the stitch-forming mechanism and symmetrically with respect to the center line of the throat-plate.
- The throat-plate 15, as shown in Figs. 2 and 5, is cut with feed-way slots 16 and 17 extending from a point in front of the needle-holes 15' and diverging outwardly in a direction away from the operator. These slots are adapted to receive the long arm-like sections 11 and 12 of the feed-dog during their rising and feeding movements. The throat-plate has also a slot or slots 18 to receive the intermediate feeding surfaces 14.
- The carrier 7 is connected through feed-lever 19 to a bellcrank 20 which latter receives its motion from an eccentric on the main-shaft 5 to give to the feed-dog its stitch-length movement. An eccentric 21 on the forward end of shaft 5 gives the feed-lift movement.
- In carrying the present method into effect the two fabric sections *a b* are first joined in the usual manner either by means of the well known through-and-through stitching *d*, illustrated in Fig. 9, or by means of the well known overlock stitching *e*, illustrated in Fig. 11. The sections *a b* are then opened out until the major portions thereof lie substantially in the same plane, as shown in Fig. 7. A strain is next exerted upon the fabric sections in opposite directions away from and transversely of the line of initially formed stitches *d* or *e* and the connected parallel lines of stitches *f* are applied while the fabric sections are held stretched and flattened, as shown in Fig. 8.
- In utilizing a machine such as above de-
- scribed for carrying the invention into effect, the previously stitched work, after having been opened out, may be guided to the covering stitch-forming mechanism by means of the usual guide-fin 22 on the presser-foot 23 secured to the presser-bar 4. The guide-fin 22 cooperates in a well known manner with the fabric rib guideway or slot 24 formed in the throat-plate 15 and acts to guide the initially stitched seam centrally between the needles at 3', 3'. The feed of the machine is timed as usual, that is, the feed-dog rises as the needles rise and moves lengthwise of the stitching when the needles are out of the work, the direction being indicated by the arrow *a* in Fig. 2. As the needles rise, the feed-dog rises in its advance position with the forward ends of sections 11 and 12 in a plane in front of the needles and with certain of the feeding teeth of each auxiliary section in advance of the stitch-forming mechanism; *i. e.*, in advance of a transverse line through the stitching point. When the needles are out of the work, the feed-dog is moved lengthwise of the stitching and as the sections 11 and 12 are so moved they are also moved laterally by reason of the divergent feed-way slots 16 and 17 in the throat-plate. Such lateral movement of sections 11 and 12 will stretch or take the fullness out of the work, thereby flattening the work, in which stretched and flattened condition it is held by the presser-foot when the next succeeding stitch is being made. This stretching action does not extend much beyond the needle-holes for the reason that the seam and covering stitches are supported upon and fed by the center or main section 14 of the feed-dog.
- It will be understood that the above disclosed process of forming a covering seam may be modified without departure from the spirit of the invention which consists primarily in covering the initially stitched and opened-out fabric sections, while the sections are under a transverse strain. It is essential, however, that the covering seam shall consist of parallel lines of stitching disposed on opposite sides of the stitching uniting the edges and that said parallel lines of stitching shall be connected at least on one side of the fabric. In the present instance the looper-thread constitutes the connecting means.
- While I have disclosed my improved process as applied, particularly, to the forming of a flat seam in connection with joining the edges of light elastic materials, it is apparent that it may be applied to various other flexible sheet materials.
- Having thus set forth the nature of the invention, what I claim herein is:—
1. The process of joining fabric sections consisting in uniting the superposed edges

of the fabric sections by stitching, opening
the sections of fabric until the major portions
lie in substantially the same plane, exerting
a strain on the respective fabric sec-
5 tions in opposite directions away from and
transversely of the line of stitching, and
uniting said fabric sections while under
said strain by connected parallel lines of
10 stitches disposed respectively on opposite
sides of the first line of stitching.

2. The process of joining fabric sections
consisting in uniting the superposed edges
of fabric sections by a line of through-and-

through stitching, opening the sections of
fabric until the major portions lie in sub- 15
stantially the same plane, exerting a strain
on the respective fabric sections in opposite
directions away from and transversely of the
line of stitching and passing parallel lines
of stitching of a covering seam through the 20
respective sections on opposite sides of the
first line of stitching while the fabric sec-
tions are under strain.

In testimony whereof, I have signed my
name to this specification.

GEORGE E. MOLYNEUX.
